UNITED STATES PATENT OFFICE.

MILLARD F. BOTKIN, OF KANSAS CITY, MISSOURI.

EXTENSIBLE WAGON-BED.

1,293,679.

Specification of Letters Patent.

Patented Feb. 11, 1919.

Application filed May 23, 1918. Serial No. 236,203.

To all whom it may concern:

Be it known that I, MILLARD F. BOTKIN, a citizen of the United States, residing at Kansas City, in the county of Jackson and State of Missouri, have invented a new and useful Extensible Wagon-Bed, of which the following is a specification.

My invention relates to extensible wagon beds in which the sides and ends are provided with extensions adapted to increase its capacity for loads of different kinds of materials and farm products and arranged to fold with the sides and ends of the bed.

The object of my invention is to provide a wagon bed with facility for adapting the same for carrying loads of light or heavy specific gravity, such as grain, hay, vegetables, fodder, small or large animals, and other farm products equipment and stock, thereby providing a wagon bed having general utility to obviate the necessity of special beds in farming industry.

I attain these objects by the mechanism and devices illustrated in the accompanying drawing, in which—

Figure 1, is a side elevation of a wagon body embodying my invention, and showing the extensions folded;

Fig. 2, is a rear elevation of a wagon bed to which my invention is applied, and showing the extensions operative, the tail gate being removed;

Fig. 3, is a rear elevation of the wagon bed, and showing the tail gate with folded extension, the one corner supporting member being broken away to disclose the channel to receive the ends of the gate;

Fig. 4, is a plan view of the inner side of the corner supporting member and its hinged member;

Fig. 5, is a view of the leg and its toe for supporting the extensions, and showing the cotter pin piercing the toe to hold the leg in place;

Fig. 6, is an elevation of a fragment of the side of the wagon bed, and showing the corner member engaged by the supporting leg holding the extension in place, and

Fig. 7, is an end view of the tail gate, and showing the supporting leg holding the extension folded.

Similar numerals refer to corresponding parts throughout the several views.

1, is a wagon bed embodying my invention and which is mounted on a running gear 2, in the usual manner. Vertically extending

supporting members 3, are mounted permanently at the front and side edges of the upper side of a platform 4. The members 3, are made of cast or pressed metal, preferably pressed steel, and comprise a flat portion 5, of suitable dimension and having segmental flanges 6, rising upwardly from their outer sides, the flanges being provided with a series of holes 7, extending along their peripheral edges. Supporting arms 8, are hingedly connected with the upper ends of the members by hinges 9, and are adapted to move inwardly and outwardly of the members. Corner supporting members 10, are permanently mounted at the corners of the rearward end of the platform 4, and they are formed like members 3, except that they are provided on their reverse sides with channels 11, which are specially adapted to slidably receive the ends of a tail gate 12, hereinafter described. Supporting arms 13, similar to arms 8, are hingedly connected with the upper ends of the members 10, by hinges 14, and they are adapted to move inwardly and outwardly of the members. Plates 15, of suitable width, are permanently secured on the lower end portions of the inner sides of the members 3 and 10, on the sides and front end of the bed, by fasteners 16, which are entered in the openings 16, in members 3 and 10, and penetrate or pierce the plates, such as nails, screws, and bolts. Plates 17, of lesser width are similarly secured on the inner sides of the members 3 and 10, but they are spaced apart from plates 15, and from each other a distance equal to the width of the plates and a little more or less. Plates 18, substantially identical with plates 17, are permanently secured on the inner sides of the hinged arms 8, at spaced apart points adapted for allowing their entry in the spaces between the plates 15 and 17, when the arms 8, are rotated inward. The plates 18, on the arms 8, at the front end of the bed, are shortened, so that when they are carried inwardly they will not engage the inner sides of the plates 17, on the sides of the bed. Eyes 19, are mounted on the outer sides of the arms 8 and 13, adjacent the hinges 9 and 14, and legs 20, are movably connected therewith, the legs having toes 21, adapted to enter holes 7, in the members 3 and 10, and also enter the eyes 22, mounted on the inner sides of the plates 15. The outer end portions of the toes are perforated in vertical direction to receive a cotter pin 23,

or any other similar device, for the purpose of detaining the toes in the members 3 and 10, and in the eyes 22. A tail gate 12, is 5 slidably mounted in the channels 11, in the corner members 10, and is thereby removably secured on the bed. The tail gate consists of a lower plate 25, like plates 15, and spaced apart plates 26, like plates 17, which plates are secured on the inner side of two members 10, 3, having hinged arms 8, the ends of the plates being adapted to enter the channels 11, in the corner members 10. Plates 27, similar to plates 26, are secured on the inner sides of the arms 8, at spaced apart points 15 adapted to allow their entry in the spaces between the plates on the members 3, when the arms are rotated inward. The plates 27, are shorter than plates 26, so that when the gate is in place their ends will be closely adjacent the inner sides of the plates on the sides of the bed. The members 3, on the tail gate are not secured on the platform 4, as is the case with the members at the sides and front end of the bed. Members 3, on the tail 20 gate, are likewise provided with eyes 19, and legs 20, having toes 21, and eyes 22, on the gate to receive the toes to detain the legs, as 25 shown in Fig. 7.

The wagon bed organized as above described provides facility for converting the bed to any use without tools or implements being employed, or removing the bed from the running gear. If the bed is desired for ordinary use to receive a load, such as 30 grain, vegetables, coal, wood, or the like, the side extensions 28, the front end extension 29, and the tail gate extension 30, are folded with the permanent sides, front end, and tail gate, as shown in Figs. 1 and 3. If animals 35 are carried, the extensions are rotated to vertical position, as may be seen in Figs. 2 and 6; in the former figure the front extension is vertically extended, the side extensions being shown vertical by dotted lines, and in the latter figure the tail gate extension is shown 40 in vertical position. In practice, the front extension, preferably, is positioned vertically when extended, and the same preference applies to the tail gate extension, it being 45 understood that either extension may be detained at any angle. If hogs are to be carried, or any other small animal, or fowl, are 50 to be transported, the side extensions may be detained in horizontal position, as shown by dotted line, at 31, in Fig. 2. If hay, straw, fodder, or other light material is to be trans-

ported, the side extensions are rotated outwardly to horizontal position, and there detained, as is shown at 32, in Fig. 2.

To detain the extensions at any desired angle, the toes 22, of the legs 20, are entered into the holes 7, in the members 3, which are best adapted to provide the desired angle, the cotter pin being entered in the toes to detain the legs in place. When the extensions are folded with the permanent sides of the bed, the legs are detained by entering their toes into the eyes 22, and securing them in place by the cotter pins.

Having described my invention what I claim is—

An extensible wagon bed, consisting of a platform, supporting members mounted vertically at the sides and front end of said platform and provided outwardly with perforated flanges extending in the form of segments, the inner sides of the members at the rear corners of the platform being provided with channels, arms hingedly connected with the upper ends of said supporting members and provided outwardly with movable legs having toes adapted to selectively enter the perforations in the flanges on the members to detain the arms, spaced apart plates mounted on the inner sides of said supporting members, spaced apart plates mounted on the inner sides of said arms and adapted to enter and leave the spaces between the plates on said supporting members, and a tail gate slidably mounted in the channels in said supporting members at the rearward corners of said platform, said tail gate comprising a plurality of vertically extending supporting members provided outwardly with perforated flanges extending in the form of segments, arms hingedly connected with the upper ends of said supporting members and provided outwardly with movable legs having toes adapted to selectively enter the perforations in the flanges on the supporting members to detain the arms, spaced apart plates mounted on the inner sides of said arms and adapted to enter and leave the spaces between the plates on said supporting members.

Kansas City, Missouri, May 18th 1918.
